UNITED STATES PATENT OFFICE.

JOHN E. MARSDEN, OF PHILADELPHIA, PENNSYLVANIA.

WINDOW-REGULATOR.

1,229,769.

Specification of Letters Patent. Patented June 12, 1917.

Application filed June 18, 1914. Serial No. 845,806.

To all whom it may concern:

Be it known that I, JOHN E. MARSDEN, a citizen of the United States, residing in the city of Philadelphia, county of Philadelphia, and State of Pennsylvania, have invented a new and useful Window-Regulator, of which the following is a specification.

My invention resides in means for regulating the position of a window, and more particularly a vehicle window in the door of a carriage, automobile or the like. And my invention resides further, in means for locking the window in any of its positions.

For an illustration of one of the forms my invention may take reference is to be had in the accompanying drawings, in which:

Figure 1 is a side elevational view, partially in section, showing an automobile with its door having a window operated in accordance with my invention.

Fig. 2 is a vertical sectional view through the window and door, some parts in elevation.

Fig. 3 is a vertical elevational view of the window and its operating means, some parts in section, with the inner side of the door removed.

Fig. 4 is a side elevational view, some parts in section, on enlarged scale, showing the operating handle and locking means.

Fig. 5 is a vertical sectional view, some parts in elevation, of the spring counter-balancing means and one form of chain adjusting means.

Fig. 6 is a front elevational view of a modified form of means for adjusting the chain.

Fig. 7 is a fragmentary sectional view through the window glass and its associated parts.

Fig. 8 is a fragmentary sectional view through the glass showing means of attaching the same to the operating chain.

The window pane of glass 1 has on its vertical sides the channel-shaped metallic members 2 which slide vertically in the metal channels 3 carried by the outer half 4 of the door or frame, the inner half 5 of the door or frame being visible in Fig. 1 and being attached to the member 4 by any suitable means. In each of the channels 3 is preferably disposed a strip 6 of felt or the like to cause smooth or silent

movement of the window in the guiding members 3.

Across the bottom of the window glass 1 is a channel-shaped member 7 having in its opposite sides at 8 apertures in which engage the fingers 9 of the member 10, embracing member 7. To the member 10 is secured the member 11 which is attached to the sprocket chain 12. This chain 12 passes over the sprocket wheels 13 and 14, the former centered upon the pin or shaft 15 carrying the member 16 having a square hole fitting the squared end 17 of the shaft 15, such squared end 17 being riveted over as indicated at 18 to hold the member 16 in place. Carried by the member 16 are the pins 19 passing through holes in the sprocket wheel 13 and adapted to engage in holes 20 in the member 21 secured to the door member 5 and forming the bearing 22 for the rotatable shaft 15 which also passes through the member 23 secured to the member 5. The handle 24, of cut glass or other suitable material, is secured to the shaft 15 outside of the collar 25 which is adapted to move in the countersink 26 in member 23. To the member 23 is pivoted the grip or handle 27 by which the door may be pulled shut. On the inside of the member 5 is secured a spring 28 which tends to thrust the member 16 and attached parts toward the left, as viewed in Fig. 4, to enter the pins 19 into the holes 20, of which there may be a series disposed in a circle in the member 21.

The other sprocket wheel 14 is secured by rivets or screws 29 to the wall 30 of the metallic casing 31, the sprocket wheel 14 and the casing 31 being rotatable upon the non-rotatable shaft 32 secured at its end 33 in the member 34. A spiral spring 35 has its one end 36 secured to the shaft 32 while its other end is secured to the casing 31.

The screw threaded bolt 37 extends freely through the lug 38 on member 34 and carries on its upper end the nut or collar 39, so that the bolt 37 may rotate freely with respect to member 34 without substantial longitudinal play with respect to member 34. Secured to the door member 4 is a bracket 40 which is screw threaded to receive the bolt 37, and a lock nut 41 is threaded upon bolt 37. The lower end of bolt 37 is squared at 42 to receive a socket or other wrench whereby the bolt 37 may be rotated and thus

be raised or lowered with respect to stationary member 40 thereby permitting bodily movement of sprocket wheel 14, casing 31 and attached parts to stretch the sprocket 5 chain 12 to the desired tension.

The operation is as follows:

When it is desired to lower the window, the operator presses inwardly to the right, as viewed in Figs. 2 and 4, upon the handle 10 24, removing pins 19 from holes 20, whereupon the handle 24 is rotated, thus rotating the sprocket wheel 13 which drives the chain 12 which in turn drives the sprocket wheel 14. And the window 1 being attached by 15 member 11 to the sprocket chain 12 the window will be lowered. Upon release of inward pressure upon the handle 24 the spring 28 will restore the parts to the position shown in Fig. 4 bringing pins 19 into 20 other holes 20, thus locking the window in its newly adjusted position.

When the window 1 is lowered the sprocket wheel 14 drives the casing 31 thereby winding up the spring 35 which, when it 25 is desired to raise the window, assists in raising the window, and acts as a counterbalance therefor.

In Fig. 6 is shown a modified means for adjusting the tension on the chain 12. Here 30 the sprocket wheel 14 and casing 31 are pivoted upon the shaft 32^a secured non-rotatably to the member 34^a on the end of the lever 43 pivoted at 44 to the door member 4. A bracket 40^a secured to the door member 4, 35 is screw threaded to receive the bolt 37 provided with lock nut 41, the bolt 37 being freely rotatable in the ear 45 on the outer end of lever 43, a collar 46 being secured upon the upper end of bolt 37 and a spring 0 47 intervening between the collar 46 and ear 45. By turning the bolt 37 the lever 43 will be shifted on its pivot 44 to move the shaft 32^a upwardly or downwardly as required to put the desired tension upon the sprocket chain 12.

Obviously in place of the sprocket chain 12 may be used a belt or other equivalent device.

What I claim is:

1. The combination with a window, of means for moving the same comprising a window driving wheel, a rotatable and lon-

gitudinally movable shaft, a stationary member having locking notches, a member carried by and secured against rotation with 55 respect to said shaft, said shaft carrying said wheel and extending therethrough, a locking pin carried by said second named member and extending through said wheel and adapted to engage in said notches, and 60 a spring engaging the end of said shaft and opposing withdrawal of said pin from said notches.

2. The combination with a window, of means for moving the same comprising a 65 window driving wheel, a rotatable and longitudinally movable shaft, a stationary member having locking notches, a member carried by and secured against rotation with respect to said shaft, said shaft carrying 70 said wheel and extending therethrough, a locking pin carried by said second named member and extending through said wheel and adapted to engage in said notches, said pin forming a driving connection between 75 said member and said wheel.

3. The combination with a window, of means for moving the same comprising a window driving wheel, a rotatable and longitudinally movable shaft, said driving 80 wheel disposed in fixed angular relation with respect to said shaft, a stationary member having locking notches, a member carried by and secured against rotation with respect to said shaft, and a locking pin carried by 85 said second named member and adapted to engage in said notches.

4. The combination with a window, of means for moving the same comprising a window driving wheel, a rotatable and longitudinally movable shaft, a stationary member having locking notches, and locking 90 means rotatable and movable longitudinally in fixed relation with said shaft and connecting said shaft with said wheel and 95 adapted to engage in said notches.

In testimony whereof I have hereunto affixed my signature in the presence of the two subscribing witnesses.

JOHN E. MARSDEN.
